[57] **CLAIM**

The ornamental design for a plumbing fitting handle, as shown and described.

DESCRIPTION

FIG. 1 is a top perspective view of a plumbing fitting handle showing my new design;

FIG. 2 is a rear elevational view thereof, the front being a mirror image of the rear shown;

FIG. 3 is a top plan view thereof;

FIG. 4 is a right side elevational view thereof;

FIG. 5 is a left side elevational view thereof; and

FIG. 6 is a rear elevational view of a modified form of the plumbing fitting handle shown in FIG. 1, the front being a mirror image of the rear shown.

FIG. 4

FIG. 5

FIG. 6
